UNITED STATES PATENT OFFICE.

WILLIAM J. MILLER, OF SWISSVALE, PENNSYLVANIA.

APPARATUS FOR PRESSING GLASS ARTICLES.

1,130,919.

Specification of Letters Patent.

Patented Mar. 9, 1915.

Original application filed April 9, 1913, Serial No. 760,057. Divided and this application filed January 21, 1914. Serial No. 813,436.

To all whom it may concern:

Be it known that I, WILLIAM J. MILLER, a citizen of the United States, residing at Swissvale, in the county of Allegheny and State of Pennsylvania, have invented certain new and useful Improvements in Apparatus for Pressing Glass Articles, of which the following is a specification.

My invention relates to improvements in apparatus for pressing glass articles, of the type wherein the several operations are performed by automatically operative mechanism, utilizing fluid pressure, the pressed articles being formed successively within a series of intermittently rotatable molds.

The machine as a whole comprises such a table and molds, actuating mechanism for the table, means for locking and unlocking the table, plunger mechanism and operating means therefor, and shears for cutting the glass off of the supplying means for the mold.

The present invention particularly refers to the shear mechanism, the application being a division of my prior application filed Apr. 9, 1913, Serial No. 760057.

In the drawings illustrating the invention, Figure 1 is a diagrammatic view, partly in section, and partly in plan, showing the several operating parts of the complete machine in segregated arrangement, with their connected piping, etc. Fig. 2 is a vertical sectional detail view of the automatic valve mechanism for locking the table and for controlling the fluid pressure to the shears cylinder. Fig. 3 is a plan view of the entire machine, showing the relative location of the several operative mechanisms. Fig. 4 is a vertical sectional detail view of the shear mechanism, indicated by the section line IV. IV. of Fig. 5. Fig. 5 is an under plan view of the shear mechanism.

The machine as a whole consists of several main features comprising the frame of the apparatus, embodying a main stationary table carried by any suitable framework. Upon the stationary table is rotatably mounted the mold supporting table 4 of circular form, revolvably carried preferably on ball bearings around a central supporting spindle or standard, of well-known construction, whereby to centralize the mold supporting table for its intermittent revolution and operation.

Mounted upon the table 4 are a plurality of glass pressing molds 7, five being shown in the machine illustrated, so located and spaced as to be brought consecutively in register with a pair of shear blades 8, 8, and a pressing plunger located vertically above, and in registering position with each mold, as it is brought successively thereunder.

The machine is so designed and the several working parts so proportioned and arranged as to effect the cutting of the molten glass by the shears when it is held between them above the mold by the workman; to effect shifting rotation of the table carrying mold and molten glass around one space to register with the plunger; to time the operation of the table shifting mechanism under the control of the initial controlling release valve to provide sufficient time for the cutting and dropping of the glass into the mold before the table is actuated; to shift the table and to cushion or retard its actuating mechanism at the end of its movement, avoiding jars or shocks; to then automatically actuate release valve mechanism by an abutment on the table itself to set the plunger mechanism into motion by its controlling valve, embodying timing and pressure controlling valve mechanism; to withdraw the plunger; and to effect performance of these several functions through interacting and interdependent fluid pressure connections and mechanism, adapted to carry out the functions without any attention from the operator, after actuating the initial release valve, as is more fully illustrated and described in the parent application above referred to.

The shears 8 are operated by the piston of fluid controlled cylinder A. The table 4 is shifted by the piston of the fluid controlled cylinder B, mounted beneath the table with its connected parts, the fluid supply thereto having circulation through a retarding valve C under control of the automatic valve D, which is in direct communication with the initial release or bleeder valve E, the automatic valve D being directly connected to the main air supply pipe S.

The pressing plunger is mounted at the lower end of the usual spindle 10, with suitable accompanying spring mechanism for cushioning the stroke, spindle 10 extending into the plunger cylinder F mounted on the

supporting bracket 14, carried by columns or otherwise, upwardly above the main frame or table 2 of the machine. A timer G for the plunger cylinder F is mounted on the same bracket, as shown, and is directly connected with the valve casing f of plunger cylinder F, whereby to control the shifting operation thereof. A supply and exhaust fluid pressure cylinder F to effect lowering 10 of the plunger at a predetermined speed at a limited pressure is controlled by the valve within casing f and its parts, whereby to control the shifting operation thereof.

The shear actuating mechanism A consists 15 of a cylinder mounted upon one of several standards 13 extending upwardly above the stationary table 2, having a piston head 15 on the inner end of stem 16 extending out through the end of cylinder A having a 20 terminal cross head 17 provided with pins 18, 18, in notched engagement with the rear outer portions of blades 8, said blades being pivoted on a rivet or stud 19 carried in a suitable support 20 extending out underneath cross head 17.

Support 20 is loosely clamped underneath extension support a of cylinder A and is held thereto by bolts a' which pass through extension a and are tapped in a cross bar a² 30 which in turn is connected by soldering or otherwise to a leaf spring a³ extending out underneath the pivoting portions of the shear blades 8 to hold them together in shearing contact. By this means bar a² and support 35 20 are held tightly in position. The shears and support 20 may thus be bodily removed by loosening bolts a', the construction effecting close adjustment of the shears with relation to each other and the top of the 40 mold, and quick changing of the blades. Fluid pressure is supplied to the cylinder A by branch pipe 21 which is in direct communication by its upper terminal with the interior of automatic valve D.

45 Valve D has a four-fold function; first, to unlock and lock the rotatable table 4 by its reciprocable stem 22 having the tapered terminal adapted to engage with the registering socket 23 in the under portion of table 50 4, under control of the initial release valve E; second, to admit direct air pressure to cylinder A to close the shears upon actuation of release valve E, and to open the shears; third, to supply retarded air pressure to the table shifting cylinder; and 55 fourth, to supply air pressure to the other end of shifting cylinder B to reverse the shifting mechanism for the next movement. To this end the automatic valve D is provided 60 in its lower portion with a cylindrical valve chamber d', within which is mounted the vertically reciprocating controlling valve d² connected with the lower end of plunger rod 22, as shown in Fig. 2, the valve 65 d² having a reduced middle area or cross sec-

tion, transverse air supply ports d³ and d⁴ respectively, and an exhaust port d¹⁰ adapted to register with pipe 21 or 21^d respectively and with port d⁵ opening to the atmosphere. Inserted between the lower end 70 or cap d⁶ of the casing of valve d and the lower end of said valve d², is a cushioning spring d⁷, a minute leakage port d⁸ communicating from port d⁴ to the lower cavity of the casing. Said cavity is in communication with the release or bleeder valve E by a pipe 24, connected at its other end with the lower portion of said valve (see Fig. 1) and the releasing valve is adapted to effect release of air pressure from said cavity d⁹ 80 of valve d upon the lowering of lever e pivoted on the bracket e² of valve e. Lever e bears downwardly upon a stem e³ of an outlet valve e⁴, being normally held to its seat by a cushioning spring within valve casing e⁶.

It will be understood that in the operation of the machine, the workman having lowered the molten glass on the end of his punty rod into the upper portion of the 90 mold and in register with shear blades 8, he lowers the punty rod upon lever e at the proper movement, thereby releasing pressure through pipe 24 from cavity d⁹, whereupon the pressure in valve chamber d' immediately lowers valve d² bringing port d³ into register with pipe connection 21 and its inner terminal communicating port, as in Fig. 2, thereby establishing fluid pressure by pipe 21 to the inner end of shears cylinder A, actuating plunger 15, 15 outwardly, cutting off the glass, and dropping it into the mold.

What I claim is:

1. Shear mechanism for a glass press comprising an actuating cylinder having a bearing extension, a piston, and a stem extending through said extension; a shear pivot support extending underneath the bearing extension of the cylinder, shear blades pivoted thereto, a crosshead on the piston stem operatively engaging the blades, a clamp securing the pivot support to the bearing extension, and a spring attached to and extending from the clamp underneath the blades for holding them together and against said support in such manner that the pivot may be adjusted to or from the cylinder.

2. In an apparatus for pressing glass articles, the combination of a rotatable mold table, a shifting cylinder therefor, shears and an actuating cylinder therefor, and a controlling valve for the shears cylinder and shifting cylinder having a part forming a locking and unlocking device for the table, a fluid supply, and means for effecting release from one end of said valve to open communication to the shifting cylinder and shears cylinder and to unlock the table.

3. In an apparatus for pressing glass articles, the combination of a rotatable mold table, a shifting cylinder therefor, shears and an actuating cylinder therefor, a controlling valve for the shears cylinder and shifting cylinder having a connected co-acting locking and unlocking device for the table, an air pressure supply therefor, and a releasing valve operable to reduce pressure at one end of said controlling valve to effect shifting thereof.
4. In an apparatus for pressing glass articles, the combination of a rotatable mold table, a shifting cylinder therefor, shears and an actuating cylinder therefor, a controlling valve for the shears cylinder and shifting cylinder having a connected co-acting locking and unlocking device for the table, an air pressure supply therefor, and a releasing valve operable by the workman in delivering glass to the mold between the
5. In an apparatus for pressing glass articles, the combination of a rotatable mold table, a shifting cylinder therefor, shears and an actuating cylinder therefor, a controlling valve for the shears cylinder and shifting cylinder having a connected co-acting locking and unlocking device for the table, an air pressure supply therefor, and a release valve having a lever adapted to be depressed by the punty rod of the workman in lowering the glass into the mold between the shears and connected with one end of the controlling valve. 25
